Primary Examiner — Kelley Donnelly(74) *Attorney, Agent, or Firm* — NSIP Law(57) **CLAIM**

We claim the ornamental design for a table top for a display stand, as shown and described.

DESCRIPTION

FIG. 1 is a front perspective view of a table top for a display stand showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a reference view thereof, in which a table top for a display stand is applied.

The broken lines in the figures show portions of a table top for a display stand which are environmental structure and form no part of the claimed design.
